UNITED STATES PATENT OFFICE.

WILLIAM W. McCAY AND CLARENCE G. McCAY, OF CHICAGO, ILLINOIS.

RECEPTACLE.

1,243,315.

Specification of Letters Patent. Patented Oct. 16, 1917.

Application filed December 22, 1916. Serial No. 138,406.

To all whom it may concern:

Be it known that we, WILLIAM W. McCAY and CLARENCE G. McCAY, citizens of the United States, residing at Chicago, in the county of Cook and State of Illinois, have invented new and useful Improvements in Receptacles, of which the following is a specification.

This invention relates to receptacles which are constructed of paper, pasteboard or analogous material, and its object is to provide a receptacle of this kind which is strong and durable, and which can be easily and cheaply manufactured.

The invention also has for its object to provide a paper receptacle of the kind stated which can be refilled and used many times, and which is so constructed that if it is damaged, the damaged part can be replaced at a trifling cost.

The objects stated are attained by means of a novel combination and arrangement of parts to be hereinafter described and claimed, and in order that the same may be better understood, reference is had to the accompanying drawings forming a part of this specification.

In the drawings,

Figure 1 is a plan view of one of the members out of which the receptacle is constructed;

Fig. 2 is a plan view showing a second member;

Fig. 3 is a perspective view of another member;

Fig. 4 is a perspective view showing the three members partly assembled;

Figs. 5 and 6 are sections on the lines 5—5 and 6—6, respectively, of Fig. 7, and

Fig. 7 is a perspective view of the finished receptacle closed and ready for mailing or shipping.

Referring specifically to the drawings, the receptacle is made up of three parts, each of which is formed of a single sheet of paper, pasteboard or similar material. The part shown in Fig. 1 is an elongated sheet having folds 11 along its longitudinal edges for reinforcing the same. The sheet is folded on the dotted lines 12 to form alternating wide and narrow sections. A narrow section 13 is at one end of the sheet, which is succeeded by a wide section 14, a narrow section 15, a wide section 16, a narrow section 17, a wide section 18 and a

narrow section 19, the sheet at this end terminating in a tongue 20.

The member shown in Fig. 2 is also a sheet comprising a main body portion 21 having long flaps 22 at its longitudinal edges, short flaps 23 at the same edges and one at each end of the long flaps.

The member shown in Fig. 3 is a strip which is bent and secured at its ends to obtain a rectangular contour, the sides being indicated at 24 and the ends at 25.

In assembling the hereinbefore described parts, the flaps 22 are bent over to lie on top of the sheet 21, and the end portions of the sheet are bent upward at a right angle 70 on the dotted lines 26 and also folded on themselves on the dotted lines 27 to form end walls of two thicknesses of material, said walls being shown at 28 and 29, respectively. The short flaps 23 are bent up 75 with the end portions of the sheet and are then bent to extend inward of the end walls formed by said bent up end portions, said flaps now coinciding with the longitudinal edges of the main body 21 of the sheet reinforced by bending over the flaps 22. The member shown in Fig. 3 is now placed over 80 the end walls and side walls formed by bending the ends of the sheet 21 and the flaps 23, the end walls 25 coinciding with 85 and fitting the outside of the wall section 28, and the side walls 24 fitting outside the side flaps 23 bent as hereinbefore described.

The two members shown in Figs. 2 and 3 have now been assembled to produce a receptacle in the form of a shallow tray open 90 on top. The parts 21 and 22 form the bottom of the tray, the parts 28, 29 and 25 the end walls, and the parts 24 and 23 the side walls of the tray, said parts 24 being reinforced at their ends by the short flaps 23.

The member shown in Fig. 1 forms a wrapper which reinforces the tray and also provides a closure therefor. The tray and the wrapper are connected in the following 100 manner:

Before the bends at 26 and 27 are made, the sheet 10 is placed on top of the part 21 and the folded flaps 22, inside the end walls formed by the parts 28 and 29 and beneath 105 the flaps 23, the sheet being so positioned that its section 16 coincides with said parts 21 and 22. The tray bottom is therefore reinforced by the section 16, which latter is also reinforced by the folds 11. The mem- 110

ber shown in Fig. 3 is now applied as hereinbefore described, after which the folding of the wrapper may proceed. The section 15 of the wrapper is bent up at right angles 5 to the part 16 to coincide with one of the side walls of the tray, and the part 14 is bent over across the open top of the tray, with the end section 13 extending down along the outside of andlapping the other 10 side wall of the tray. The section 17 is now bent up to envelop the outside of the part 13, the part 18 is folded over on top of the part 14, and the part 19 is folded down to overlap the outside of the part 13. The 15 tongue 20 is now tucked in between the parts 16 and 21 which form the bottom of the receptacle.

A reversal of the hereinbefore described operation opens up the receptacle, which can 20 be readily done. The receptacle can therefore be refilled and used again, and this can be done many times, as all the walls are reinforced, and rendered sufficiently strong to withstand rough handling. The receptacle is 25 well adapted for parcels post, express, and freight shipments, or any other purpose for which a cheap, light and durable receptacle is required. It will be understood of course that the receptacle must be filled before the 30 application of the wrapper is completed. Fig. 4 shows the receptacle ready for filling and closing.

We claim:—

1. A receptacle comprising a tray composed of a blank which is foldable to form 35 a bottom, side and end walls, and a reinforcing strip fitting over the side and end walls, in combination with a wrapper composed of a blank having a portion seating 40 on the tray bottom inside the end walls and beneath the side walls, and provided with parts enveloping the side walls of the tray and extending across the top thereof, one end of the wrapper having a tongue adapted 45 to be tucked in between the tray bottom and that portion of the wrapper which seats thereon.

2. A receptacle comprising a tray com-

posed of a blank which is foldable to form a bottom, side and end walls, and a reinforcing strip fitting over the side and end walls, in combination with a wrapper composed of a blank having longitudinal edge reinforcing folds and a portion seating on the tray bottom inside the end walls and beneath the side walls, and provided with parts enveloping the side walls of the tray and extending across the top thereof, one end of the wrapper having a tongue adapted to be tucked in between the tray bottom and that portion of the wrapper which seats thereon. 50 55 60

3. A receptacle comprising a tray composed of a blank which is foldable to form a bottom, side and end walls, the end walls having a double thickness of material and a reinforcing strip fitting over the side and end walls, in combination with a wrapper composed of a blank having a portion seating on the tray bottom inside the end walls and beneath the side walls, and provided with parts enveloping the side walls of the tray and extending across the top thereof, one end of the wrapper having a tongue adapted to be tucked in between the tray bottom and that portion of the wrapper which seats thereon. 65 70 75

4. A receptacle comprising a tray composed of a blank which is foldable to form a bottom, side and end walls, and a reinforcing strip fitting over the side and end walls, 80 in combination with a wrapper composed of a blank having a portion seating on the tray bottom inside the end walls and beneath the side walls, and provided with parts enveloping the side walls of the tray and extending 85 across the top thereof, the two ends of the wrapper overlapping at the top and side walls with a double thickness of material, one end of the wrapper having a tongue adapted to be tucked in between the tray 90 bottom and that portion of the wrapper which seats thereon.

In testimony whereof we affix our signatures.

WILLIAM W. MCCLAY.
CLARENCE G. MCCLAY.
